(57) **CLAIM**

The ornamental design for a fluid product dispenser, as shown and described.

DESCRIPTION

FIG. 1 is a perspective view of the top and front of a fluid product dispenser according to a first embodiment showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of the top and front of the fluid product dispenser shown in FIG. 1 with the cover in place;

FIG. 9 is a perspective view of the top and front of a fluid product dispenser according to a first embodiment showing our new design;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof; and,

FIG. 16 is a perspective view of the top and front of the fluid product dispenser shown in FIG. 9 with the cover in place.
